(57) **CLAIM**

The ornamental design for a front lip splitter, as shown and described.

DESCRIPTION

FIG. 1 is a top-front-left perspective view of a front lip splitter showing my new design;

FIG. 2 is a bottom-front-left perspective view thereof;

FIG. 3 is a top-rear-right perspective view thereof;

FIG. 4 is a bottom-rear-right perspective view thereof;

FIG. 5 is a front elevated view thereof;

FIG. 6 is a rear elevated view thereof;

FIG. 7 is a top plan view thereof;

FIG. 8 is a bottom plan view thereof;

FIG. 9 is a right elevated view thereof; and,

FIG. 10 is a left elevated view thereof.

The broken lines illustrate portions of the front lip splitter which form no part of the claimed design.
